UNITED STATES PATENT OFFICE.

JOHN R. WHITTEMORE AND JOHN F. MORGAL, OF INDIANAPOLIS, INDIANA.

INSERTED-CUTTER-BLADE HOLDER.

No. 895,218.

Specification of Letters Patent.

Patented Aug. 4, 1908.

Application filed October 18, 1907. Serial No. 398,123.

To all whom it may concern:

Be it known that we, JOHN R. WHITTEMORE and JOHN F. MORGAL, both of Indianapolis, county of Marion, and State of Indiana, have invented a certain new and useful Inserted-Cutter-Blade Holder; and we do hereby declare that the following is a full, clear, and exact description thereof, reference being had to the accompanying drawings, in which like letters refer to like parts.

The object of this invention is to improve the means for holding inserted cutter blades more securely and steadily in place. To this end we combine with the housing or cutter head and the cutter or blade therein, a thimble beside the cutter or blade held in place by a screw bolt entering the housing, the adjacent surfaces of said thimble and blade being correspondingly opposite and recessed to receive a locking block for holding the blade in place.

The nature of this invention will be understood from the accompanying drawings and the following description and claims.

Figure 1 is a plan view of the milling cutter. Fig. 2 is a side elevation of the cutter partly broken away and partly in section and with some of the blades removed. Fig. 3 is a side elevation of a blade. Fig. 4 is a perspective view of the locking block. Fig. 5 is a side elevation of the thimble.

In detail 10 is the housing or cutter head adapted to be secured upon any suitable shaft or spindle 11, whereby the housing will be driven. The housing has in its periphery transversely extending grooves 12 to receive the blades or cutter 13. These blades or cutters are elongated pieces of steel with the cutting edge along one side, on end or both on end and side. In one side of the blade a pair of recesses 14 are made side by side and near each other. The recess has two surfaces, a back flat surface arranged angularly with reference to the surface of the knife, and a curved, crescent-shaped surface, the points of the crescent extending towards the cutting edge of the knife. In other words, the recess is so formed as to receive about half of the cylindrical locking block 15, the flat end of the locking block engaging the flat inner surface of the recess and the periphery of the locking block resting against the curved surface of the recess. A recess 16 is also formed in the periphery of the housing 10 and adjacent to the transverse groove 12. This circular recess is adapted to receive the

thimble 17, which is cylindrically and centrally apertured to receive the screw bolt 18 that extends through said thimble with a fillister head and screws into the body of the housing 10. The thimble 17 is provided on its periphery with a recess 19 substantially the same as the recesses 14 in the blade excepting that the curved surface in said recess 19, which is crescent-shaped, has its points 65 projecting inward towards the middle of the housing, being arranged just the reverse of the curved surfaces of the recesses 14 in the blade.

When assembled the cylindrical locking block fits in the recesses 14 and 19, they registering with or being opposite to each other. When the screw bolt is tightened it holds the thimble down, the thimble holds the locking block and the locking block holds the blades 75 in place. It is noted that the cutter is not held in place by engagement therewith of the thimble as the blade and thimble need not necessarily touch each other, nor is the locking block held in place by the contact of the 80 screw bolt, as they need not touch each other. In fact, not more than two parts of the combination need necessarily touch each other, the action being successive from the bolt to the thimble, from the thimble to the locking 85 block and from the locking block to the blade, so that considerable binding force is exerted upon the blade. By reason of the cylindrical locking block and the corresponding recesses in the blade and thimble, the 90 blade will be held from a longitudinal movement as well as from any movement radially of the housing. This holds the blade in place while its end may be used, as well as while its longitudinal edge may be used.

Whenever the end of the cutter or knife has been considerably worn, or if for any reason there needs to be an adjustment of the position of the blade, this is rendered possible by the plurality of the recesses 14 in each 100 blade.

The parts are so formed that when first assembled, the thimble will not extend to the bottom of the recess in the housing in which it is mounted, so the strain will all come on 105 the blade, and it thus will be securely bound and held in place. A radial adjustment of the wear of the blade is secured by inserting one or more liners 20 under the blade.

What we claim as our invention and desire 110 to secure by Letters Patent is:

1. The combination of a housing grooved

2

to receive a blade and recessed to receive a thimble adjacent thereto, a blade in said groove provided with a recess in its side, a thimble beside the blade with a recess registering with the recess in the blade, the two recesses having similarly formed opposing surfaces, a locking block fitting in the recesses in the blade and thimble, and a bolt for securing said thimble to the housing 10 whereby the sleeve resists the tendency of the blade to escape from the groove.

2. The combination of a housing grooved to receive a blade and recessed to receive a thimble adjacent thereto, a blade in said groove provided with a recess in its side, a thimble beside the blade with a recess registering with the recess in the blade, said recesses in the blade and thimble having opposing inner flat surfaces and opposing concave 20 surfaces, a cylindrical locking block fitting in the recesses in said blade and thimble, and a

screw bolt for securing the thimble to the housing.

3. The combination of a housing grooved to receive a blade and recessed to receive a 25 thimble adjacent thereto, a blade in said groove provided in its side with a plurality of recesses side by side, a thimble beside the blade with a recess registering with one of the recesses in the blade, a locking block fitting in the corresponding recesses in the blade and thimble, and a bolt for securing said thimble to the housing. 30

In witness whereof, we have hereunto affixed our signatures in the presence of the 35 witnesses herein named.

JOHN R. WHITTEMORE.
JOHN F. MORGAN.
